WALL CLEANER

John R. Raney, Memphis, Tenn.

Application September 28, 1933, Serial No. 691,302

7 Claims. (Cl. 15—233)

This invention relates to devices for cleaning surfaces such as walls or ceilings.

The primary object of the invention is to provide an improved cleaner for walls or the like, which includes a cleaning element of sponge rubber and a holder and handle therefor, whereby the sponge rubber may be effectively applied to the surfaces to be cleaned.

Further objects of the invention are:

10 To provide a cleaning element comprising a tubular member of sponge rubber and a holder therefor which may be disposed within the tubular element and caused to firmly and effectively hold the element;

15 To provide means permitting the tubular member to be shifted relatively to the holding part, whereby the entire surface of the cleaning element may eventually be brought into use;

20 To provide a tubular element which may be turned inside out whereby the original inner surface may be caused to become the outer surface and be utilizable as the cleaning element, and

25 Generally to improve the design and construction of such a device.

The means by which the foregoing and other objects are accomplished and the manner of their accomplishment will readily be understood from the following specification on reference

30 to the accompanying drawing, in which:

Fig. 1 is a side elevation of the complete cleaner with a portion thereof broken away to show the interior construction.

Fig. 2 is a section taken as on the line II—II of Fig. 1, the handle being shown in elevation, and both figures being shown with the holding element collapsed as it would appear during insertion in, or removal from, the cleaning element.

Fig. 3 is a section taken on the same line as Fig. 2 showing the holding element expanded to grip the interior of the cleaning element.

Fig. 4 is a top view of a fragmentary portion of the cleaning element, showing a slot cut

35 therein in place of the holes elsewhere shown.

Referring now to the drawing in which the various parts are indicated by numerals, 10 is an elongated tubular cleaning element preferably of sponge rubber within which is an expandable

40 member, or holder, comprising two separable parts 11 and 12 which preferably are substantially semi-cylindrical in exterior conformation. Substantially at the center, both longitudinally and transversely the part 12 is interiorly

45 threaded to receive the shank 13 of a handle 14, the threading preferably being accomplished by securing a nut 15 in such part 12. The shank 13 of the handle 14 projects through the

50 part 11, whereby tightening of the handle,

forces the parts 11 and 12 apart as shown in Figure 3 thus expanding the expandable member and causing same to grip the interior of the tubular cleaning element 10.

Firmly secured in one of the parts, as the part 12, are rivets 17, one only showing in the views. These rivets are slidably mounted in the opposite part, as the part 11, with their heads 18 in suitable pockets 19 formed in such part whereby the rivet heads prevent excessive separation of the parts.

20 is a clamping plate against which the handle 14 seats, and which plate is forced by the handle, when tightened, against the cleaning member and effectually clamps the same against the holder part 12. Preferably the clamping plate 20 is provided with an inwardly extending tubular part, or sleeve, 21 which permits the

55 passage of the shank 13 and houses such shank in part, particularly that part of the shank 20 which is within the sponge rubber. Preferably the length of the sleeve 21 is such that it seats against the nut 15 immediately before the limit bolts become effective.

It will be understood that a suitable hole 22 is made in the part 12 to receive the shank 13 of the handle and that in case a clamp is used having the sleeve 21, the hole 22 is of sufficient size to receive such sleeve. A corresponding opening is made in the

60 tubular sponge rubber element, and preferably an oppositely disposed opening 23 is also made therein whereby the tubular member may be engaged on the holding member in either of two positions substantially 180 degrees apart. It will be understood that these holes need not be cylindrical

65 but that a cut 23A as shown in Fig. 4 may be substituted, it being feasible to insert the shank or tubular part through such a slit, and in some cases advantageous to have a slit in the outer surface rather than an actual hole.

70 In assembling the device the handle and clamping plate are removed and the collapsed expandable member slid into place within the tubular sponge rubber element 10, one of the holes in the tubular element being aligned with the hole 22 in the expandable member. The clamping plate is then put into position with the sleeve 21 extending through the opening in the sponge rubber into the aligned opening 22

75 in the expandable member part 12. The shank 13 of the handle is inserted through the sleeve 21, engaged with the nut 15 and run therethrough, forcing the part 11 away from the part 12 and at the same time causing the clamp

80 to compress the sponge rubber and grip same against the part 12. Separation of the parts 11 and 12 is limited by bottoming of the sleeve 21 and/or by the limit bolts 17 as the case may be.

85 It will be evident that under continued use the sponge rubber will wear down on both sides

and also diametrically opposite the handle leaving that portion adjacent the handle practically unused. In such event the handle may be removed, the sponge rubber element be turned 5 180 degrees about its longitudinal axis and the handle re-engaged thus bringing the unworn portion of the cleaning element into position for use. If desired additional holes may be made in the sponge rubber element, whereby other 10 positioning may be accomplished.

It will also be understood that, should it become desirable on account of wear, or fouling of the surface of the cleaning element, or other reason, the tubular cleaning element may be 15 removed from the holding element and be turned inside out whereby to present a fresh cleaning surface for use.

It will be further understood that as clearly shown in the drawing the tubular cleaning 20 element preferably overhangs the ends of the holding element, so that the end portions of the cleaning element may bend over the ends of the holding element and be effective in corners or the like, and also so that damage may not 25 occur from the hard ends of the holding element engaging surfaces at an angle to those being cleaned.

What I claim is:—

1. A cleaner including a tubular cleaning element; a holding member disposed therewithin, 30 said holding member comprising a pair of complementary parts, movable laterally apart, and having means limiting the separation of such parts; a clamping plate disposed along and exterior to said element, said clamping plate, 35 said element, and one of said parts having aligned apertures, said part aperture being threaded; and a handle having a threaded shank of reduced size adapted to pass through said 40 aligned apertures into contact with the unapertured one of said parts and having screw engagement with said threaded aperture, said shank cooperating with said parts to separate them, and the shoulder formed at the junction of said shank and handle clamping said plate against said element.

2. A cleaner, including a tubular cleaning element; a holding member disposed therewithin, 50 said holding member comprising a pair of complementary parts, movable laterally apart, a clamping plate disposed along and exterior to said element, said clamping plate, said element, and one of said parts having aligned apertures, 55 said part aperture being threaded; and a handle having a threaded shank of reduced size, adapted to pass through said aligned apertures into contact with the unapertured one of said parts, and having screw engagement with said 60 threaded aperture, said shank cooperating with said parts to separate them, and the shoulder formed at the junction of said shank and handle clamping said plate against said element.

3. A cleaner, including a tubular cleaning element; a holding member disposed therewithin, 65 said holding member comprising a pair of complementary parts, movable laterally apart, and having means limiting the separation of such parts; a clamping plate disposed along and exterior to said element, said clamping plate being apertured and having an inwardly projecting sleeve aligned with the aperture, said element and one of said parts, having aligned apertures, said element aperture and the outer 70 portion of said part-aperture being of size to receive said sleeve, the inner portion of said

part aperture being threaded; and a handle having a threaded shank adapted to pass through said sleeve and aligned apertures into contact with the unapertured one of said parts and having a screw engagement with said threaded aperture, said shank cooperating with said parts to separate them and the shoulder formed at the junction of said shank and handle clamping said plate against said element.

4. A cleaner, including a tubular cleaning element; a holding member disposed therewithin, 80 said holding member comprising a pair of complementary parts, movable laterally apart, a clamping plate disposed along and exterior to said element, said clamping plate being apertured, and having an inwardly projecting sleeve aligned with the aperture, and of length to pass through said element and to abutting contact within said part, said element and one of said parts having aligned apertures, said element aperture and the outer portion of said part aperture being of size to receive said sleeve, the inner portion of said part aperture being of reduced size to form an abutment for such sleeve, 85 said inner portion being threaded; and a handle having a threaded shank adapted to pass through said sleeve and apertures into contact with the unapertured one of said parts and having screw engagement with said threaded aperture, said shank cooperating with said parts to 90 separate them, the shoulder formed at the junction of said shank and handle clamping said plate against said element.

5. A cleaner, including a pair of complementary elongated parts movable laterally apart, 95 one of said parts having a threaded opening leading therethrough toward the other of said parts, a cleaning element disposed around said parts, said element being apertured to conform to said threaded opening, and a handle member 100 having a threaded shank adapted to pass through said element aperture and in screw engagement, through said threaded opening into abutting engagement with the other of said parts.

6. A cleaner, including a pair of complementary elongated parts, movable laterally apart, one of said parts having a threaded opening leading therethrough toward the other of said parts, means for limiting separation of said parts, 110 a cleaning element disposed around said parts, said element being apertured to conform to said threaded opening, and a handle member having a threaded shank portion passing through said element aperture, and in screw engagement 115 through said threaded opening into abutting engagement with the other of said parts.

7. A cleaner including a pair of complementary elongated parts, movable apart, a pair of guide members secured to one of said parts and 120 projecting therefrom substantially through the other of said parts, said latter part being apertured to receive said guide members, one of said parts having a threaded opening leading therethrough toward the other of said parts, a cleaning element disposed around said parts, 125 said element being apertured to conform to said threaded opening, and a handle member having a threaded shank portion passing through said element aperture, and in engagement with and 130 passing through said threaded opening into abutting engagement with the other of said parts.

JOHN R. RANEY.
